J.E. Hanes,

INVENTOR.

BY
Geo. Himmel ATTORNEY.

UNITED STATES PATENT OFFICE.

JARNETT E. HANES, OF ALMA, ILLINOIS.

AXLE STRAIGHTENER.

Application filed October 20, 1921. Serial No. 509,103.

To all whom it may concern:

Be it known that I, JARNETT E. HANES, a citizen of the United States, residing at Alma, in the county of Marion and State of Illinois, have invented certain new and useful Improvements in Axle Straighteners, of which the following is a specification.

This invention relates to devices for straightening accidentally bent bodies, such as the axles of vehicles, more particularly metal axles of buggies, carriages, and the like, and has for one of its objects to simplify and improve the construction, and increase the efficiency and utility of devices of this character.

Another object of the invention is to provide a device of this character which may be readily adjusted to axles of different lengths and to bends or crooks at various portions of the axle and without requiring the removal of the axle from the body or the removal of the wheels from the axle.

With these and other objects in view, the invention consists in certain novel features of construction as hereinafter shown and described and then specifically pointed out in the claim, and in the drawings illustrative of the preferred embodiment of the invention;—

Figure 1 is a plan view of the improved implement applied to a conventional axle.

Fig. 2 is a transverse section on the line 2—2 of Fig. 1.

Fig. 3 is a transverse section on the line 3—3 of Fig. 1.

Figs. 4 and 5 are detached perspective views of two forms of the axle-engaging blocks.

The improved device comprises a relatively heavy rigid beam 10 of any suitable material or of any suitable size.

An axle clamping strap 11 bent into elongated U-shape is pivoted at 12 to the beam 10 at one end and engages around the axle, represented at 13, at a point remote from the bend which is to be eliminated.

The sides of the clamping strap are provided with a plurality of spaced apertures for the pivot 12, so that the beam 10 may be adjusted nearer to or farther from the axle.

At its opposite end the beam is apertured to receive a pull rod 14, the latter having a terminal hook 15 to engage the axle and threaded for the major portion of its length

as shown. A nut 16 engages the threaded portion of the pull rod, being preferably of the lever nut form to enable the nut to be readily rotated.

By this means, the nut may be forcibly rotated by the operation of the lever arm 17 extending from the nut.

Disposed between the beam and axle is a bearing block 18 of any required form, for instance of rectangular outline as shown in Figs. 1 and 5, pointed as shown in Fig. 4, or other form, as desired.

Each block 18 is provided with a holding strap 19, so that the blocks may be moved along the beam, but without being detached therefrom, to adapt the device to the location of the bend.

By this simple means when a bend or crook develops in an axle, the beam is coupled to the axle, as shown in Fig. 1, and the block 18 adjusted to a point against the "elbow" of the bend and the strap 11 and pull rod 14 adjusted to engage the axle at each side of the bend. Then when the nut 16 is rotated by force applied to the arm 17, a strong leverage force will be applied to the axle and the bend or crook eliminated.

It will be obvious that the leverage force can be materially increased by moving the block 18 to a point relatively near the coupling strap device 11. By this means the force can be adapted to the condition or location of the bend.

The pointed block shown in Fig. 4 will preferably be employed where the bend is short, while the larger block shown in Figs. 1 and 5, will be employed where the bend is relatively long.

The preferred embodiment of the invention is disclosed in the drawings and set forth in the specification, but it will be understood that modifications within the scope of the claim may be made in the construction without departing from the principle of the invention or sacrificing any of its advantages.

The improved device may be adapted without material structural change to the axles of various kinds such as buggies, carriages, trucks, automobiles or the like.

Having thus described the invention, what is claimed as new is:—

A device of the class described comprising a beam member having a transverse aperture at one end and a vertical aperture in the other end, a block slidably bearing on

said beam adapted to engage an axle, a U-shaped strap engaging around said beam and connected to said block and slidably coupling the block to the beam, another U-shaped strap having a plurality of transverse apertures through its side portions and adapted to engage around the axle, a transverse pin engaging through one pair of the apertures of the last mentioned strap and likewise through the transverse aperture of

the beam member, a threaded rod extending through the vertical aperture of the beam and having means for detachably engaging the rod at one end with the axle, and a nut device engaging the threads of the rod and bearing against the beam. 15

In testimony whereof, I affix my signature hereto.

JARNETT E. HANES.
